CIRCUIT BREAKER ISOLATING DEVICE

William E. Welsh, Allentown, Pa., assignor to
McGraw Electric Company, Milwaukee, Wis., a
corporation of Delaware

Application August 9, 1950, Serial No. 178,467

10 Claims. (Cl. 200—48)

1

This invention relates to electrical circuit breaker structures and particularly to a device for temporarily isolating circuit breakers without interruption of line current.

It is an object of this invention to provide a convenient device for by-passing circuit breaker terminal connections without interruption of line current.

Another object of this invention is to provide a device for by-passing circuit breakers in order to facilitate maintenance of these circuit breakers without necessitating their removal from mounting brackets.

A further object of this invention is to provide a labor saving device for facilitating the disconnection of circuit breaker terminals from line without interruption of line current, necessitating the easy removal of only one clamping device on either side of the breaker.

Still another object of this invention is to provide a device for by-passing electrical circuit breakers from line without interruption of line current that will permit maintenance of the breaker in the safest possible manner without the necessity for using cumbersome insulating barriers and other protective devices.

A still further object of this invention is to provide a by-pass device for electrical circuit breakers that may be easily and inexpensively manufactured and installed.

These and other objects will appear as the description proceeds, and the scope of the invention will be set forth in the appended claims.

In the above as well as in the following description, the term "circuit breaker" is intended to describe any electrical devices that are equipped with at least two terminals adapted to be connected with the line and means electrically connecting these terminals adapted to interrupt electrical current normally flowing between the terminals; viz., housed and unhoused switches, oil circuit breakers, dry circuit breakers, fuse cutouts, and the like.

In the drawings:

Fig. 1 is a side elevational view of the novel device as employed with a conventional air-break switch joining each of the terminals with the line and diagrammatically indicating a temporary parallel circuit connection with the line.

Fig. 2 is a fragmentary top plan view of the device as installed on one side of a conventional airbreak switch.

Fig. 3 is a fragmentary side elevational view of a modification of the novel device as employed on a conventional airbreak switch.

2

Referring in detail to Fig. 1, reference character 1 refers generally to a disconnecting switch substantially the same as shown in U. S. Letters Patent No. 2,431,147, granted to Alwin G. Steinmayer on November 18, 1947, and assigned to the same assignee as the present invention. As mentioned above, the device will work equally well with any circuit breakers having at least two terminals and an interrupting means such as the switch blade, fuses, etc. The following description includes the Steinmayer switch as an explanatory aid only, and is not intended to limit the novel switch by-passing device in any manner.

15 The switch 1 includes three stacks of insulators 2, 3, and 4, supported by a base 5 which is normally grounded or neutralized. The insulator 4 carries a stationary contact 6 and a terminal 7 which is in electrical connection with said contact. Also in contact with the terminal 7 is a pair of flaring arcing horns 8. The insulator stack 3 rigidly carries a terminal 9, which terminal is also supported from the insulator stack 2. The insulator stack 2 and upper member 10 are provided with an upstanding portion 11 which is revoluble within the terminal 9, the terminal 9 thereby forming a brace between the insulator stacks 2 and 3. The switch arms 13 are pivoted on pivot support 14 supporting pivot pin 15, which supports are rigid with the terminal 9 and supported by the insulator stacks 3. The interfacing of the pivot supports 14 act as contact surfaces with the switch arms 13, which switch arms electrically connect said terminals 9 with contact 6 supported by insulator stack 4.

20 An idler link 16 is pivotally mounted on pivot supports 14 and is pivoted to a connecting link 17, the link 17 being operatively connected to the switch arms 13 for raising and lowering the switch arm as will hereinafter appear. An operating crank 18 forms a rigid part of the upper member 10, and is provided with a crank pin 19 which carries an intermediate link 20. The intermediate link 20 is pivoted to the connecting rod 21 which rod is pivoted at clevis 22. The various pivots between operating crank 18 and idler link 16 operate to provide a universal joint.

25 The stack 2 is revolubly mounted and is rotated by means of a shaft 25 or in any other suitable manner. It is apparent, therefore, that when the insulator stack 2 is rotated, the switch arms 13 will be raised or lowered as desired; thus, disconnecting or connecting the electrical circuit between terminals 9 and 7, respectively.

30 It is again to be emphasized that the novel

device is not to be limited to the switch shown and described. The Steinmayer switch is shown for illustrative convenience. It will be apparent that the device may be employed on the terminals of any circuit breaker connected with the power line.

Any convenient manner of dead-end clamping may be used with the novel by-pass device. However, a preferred manner is disclosed in Figs. 1, 2 and 3, wherein a dead-end clamp 30 is suspended from the base 5 and insulated therefrom by a string of suspension insulators 31. A string of two clevis-tongue type insulators is shown, but any number may be used depending on the desired flashover insulation requirements. Also, the insulators 31 may be of any of well-known types used for suspension purposes.

The insulator on the opposite end of the string from the dead-end clamp 30 is fastened to an extension link 32, which is in turn electrically connected to the grounded or neutralized base 5. The extension link may be omitted if desired, but is preferably provided for use with standard circuit breaker structures without requiring modification thereof. The link 32 is conveniently fastened to the base 5 by a rivet and clevis-bolt assembly 33. Since a ground or neutral connection is all that is desired, the electrical contact between the link and base will be sufficient for the purpose as shown. Rather than using the rivet and clevis-bolt assembly 33, the well-known practice of using a hock may be provided.

The extension link 32 is provided with a protruding bolt or stud 34 secured thereto with lock-nuts 35. This bolt may be positioned as desired in one of the various openings 36 provided for this purpose.

The novel by-pass device is designed to be used on both sides of the switch 1 without modification of any of the parts. The device includes a conductor which is generally referred to at 40, and which is electrically connected to either of the terminals 9 or 7 by a terminal lug 41. The lug 41 is clamped to a rigid extension arm 42. Fastened to the extension arm, at the opposite end, is a length of flexible conductor cable 43. The opposite or free end of the cable 43 is fastened to a terminal link 44, which is in turn securely fastened to a removable hot-line clamp 45. The hot-line clamp shown is one of many well-known varieties. Circumjacent to the conductor cable 43 is a helical spring 46 which is preferably co-extensive with the cable 43. Opposite ends of the spring 46 are secured to the arm 42 and terminal link 44, respectively. This may be conveniently done by forming an eyelet at both ends of the spring and holding it in place with a bolt and nut combination 47.

The hot-line clamp 45 is normally held in electrical connection with the dead-end clamp 30. This is conveniently provided for by casting a double-headed rivet or rod 50 to the dead-end clamp. The rod or rivet 50 preferably extends from both sides of the dead-end clamp for a purpose hereinafter described. It will be apparent that a stud threaded on both ends may be substituted for the rivet. This stud (not shown) would be provided with washers and stop nuts on either end as a substitute for the rivet heads. This hot-line clamp 45 is secured to the rivet 50 by tightening the fastening eyelet 51 with a hot stick (not shown).

As was stated above, substantially identical by-pass devices are used for both sides of the

switch 1. Suspended from, and in electrical engagement with, the dead-end clamps 30 are incoming and outgoing lines 55 and 56, respectively.

5 The novel by-pass device operates as follows: When maintenance operations are required on the switch 1, the lineman installs a by-pass jumper 60 from dead-end clamp 30 on the incoming line 55 to the dead-end clamp 30 on outgoing line 56, as is diagrammatically shown in Fig. 1. Releasable hot-line clamps (not shown) are fastened to both ends of the jumper 60. The jumper may then be conveniently attached to both dead-end clamps 30 by engaging 10 the jumper hot-line clamps (not shown) with rivets 58 on the portion opposite the portion supporting the hot-line clamps 45. The by-pass jumper 60 is generally protected with a length of fiber duct 61 to protect the insulation of the jumper cable from gaffing by lineman's climbers, 15 since these jumpers run underneath the circuit breaker structure.

With the jumper 60 now in place, the switch is 20 opened and hot-line clamps 45 on each side of the switch are removed by means of a hot-line stick (not shown) and fastened to the protruding bolt 34 on the link extension 32 as shown by dotted lines in Fig. 1. The machine bolt 34 may be fastened to the link in any of the openings 36, 25 which are provided as a convenient means for adjusting to desired lengths of conductor 40.

It is not necessary to make any ground connections for grounding or neutralizing the switch assembly, since the metal base 5 is ordinarily 30 grounded or neutralized with the link extension 32 electrically connected thereto. The upper switch assembly will be automatically grounded or neutralized when the hot-line clamps 45 are clamped to each of the respective protruding 35 bolts 36 on the connecting links 32.

It will be apparent that an expeditious and safe means has been provided for isolating circuit breakers during maintenance operations. Heretofore, it took linemen nearly an entire 40 day to isolate switches preparatory to making maintenance operations upon them. Also, it was necessary for linemen to install large rectangular insulated barriers (not shown) at each end of a gang of switches. These barriers were installed so that the linemen could work on top of the switch structure in complete safety without any possible contact with the incoming or outgoing lines or any parts of the structure which were energized. The insulating barriers 45 are no longer necessary with the novel by-pass device, inasmuch as all live lines and parts on live lines are now at a safe working distance from the isolated circuit breakers. Three to four 50 feet away from the base of the circuit breakers is considered to be a safe working distance for 12 to 22 kv. lines. Linemen using the novel device are now able to disconnect, maintain and reconnect at least four sets of three phase air-break switches per day, or twice the number 55 maintained by the procedure used heretofore.

Another embodiment of the novel device is disclosed in Fig. 3. This modification includes pantagraph links 70 and 71 substituted for the helical spring 46 shown in the preferred embodiment. The links offer a flexible support to the cable 43. Two or more links may be used if so desired. A terminal lug 72 is secured to the terminal 9. The end links 71 are pivotally supported by this lug at pivot bolt 73. The links 70 75 are preferably of parallel steel strips held to-

gether with bolts and spacers 16, and hingedly jointed at pivot bolt 74. The cable 43 is threaded over and under the spacers and pivotally secured at either end to bolts 73 and 75, respectively. The bolt 75 is also pivotally secured to hot line clamp 45.

This modification offers a more rigid support to the cable than the spring would, but it will be apparent that it is of a heavier structure than the preferred embodiment disclosed in Figs. 1 and 2. This modification readily lends itself to substation circuit breaker installations, and the like. Substation circuit breaker structures are of heavier ratings and are mounted on steel supports rather than on poles. The embodiment shown in Figs. 1 and 2 is preferred for circuit breakers mounted on pole brackets where one man may do all of the work with a ten foot hot-line stick.

The modified pantograph link device is operated in substantially the same manner as the preferred embodiment using the helical spring. That is, a by-pass jumper, substantially as diagrammed in Fig. 1, is installed between both dead-end clamps 30. The hot-line clamps 45 are then unfastened from the dead-end clamps 30 and moved over to the protruding bolt 34 on the link extension 32, thus grounding or neutralizing the switch.

It will be apparent that a safe and inexpensive means for by-passing a circuit breaker has been described. The novel by-pass device may be installed on existing circuit breakers without necessitating modification thereof.

Although only one switch has been disclosed in the drawings, the device readily lends itself to gang-operated switches ordinarily used in three phase connections, and may also be used in a variety of circuit breaker types. These types may include oil operated reclosers, various types of disconnect switches, fuse cutouts, or any type of circuit breakers that have at least two terminals and a means for electrically connecting or disconnecting the terminals.

I claim:

1. In an electrical circuit breaker structure including a stationary terminal, a grounded support including a dead-end anchoring means insulated therefrom and supporting said terminal in insulated relationship thereto, and a ground or neutral connection on said support; a flexible conductor including a releasable clamping means at one end on said dead-end and normally providing exclusively an electrical circuit between said stationary terminal and said dead-end anchoring means, said releasable clamping means releasably engaged with said dead-end anchoring means to temporarily disconnect the electrical circuit and releasably engageable with said ground or neutral connection.

2. In an electrical circuit breaker structure including a stationary terminal, a grounded support including a dead-end anchoring means and supporting said terminal in insulated relationship thereto, a ground or neutral connection on said support, a flexible conductor electrically connected with said stationary terminal and including a releasable clamping means normally electrically connected with said dead-end anchoring means, said clamping means releasably engaged with said dead-end anchoring means to temporarily disconnect from said dead-end anchoring means and releasably engageable with said ground or neutral connection.

3. In an electrical circuit breaker structure

including a stationary terminal, a grounded support including a dead-end anchoring means insulated therefrom and supporting said terminal in insulated relationship thereto, and a ground or neutral connection on said support; a conductor normally providing exclusively an electrical circuit between said stationary terminal and said dead-end anchoring means, said conductor comprising a flexible section, a circumjacent resilient means and a releasable clamping means releasably engaged with said dead-end to temporarily disconnect the electrical circuit and releasably engageable with said ground or neutral connection.

4. In an electrical circuit breaker structure including a stationary terminal, a grounded support including a dead-end anchoring means insulated therefrom and supporting said terminal in insulated relationship thereto, and a ground or neutral connection on said support; a conductor electrically connected with said stationary terminal and comprising a flexible section, a circumjacent resilient means and a releasable clamping means at the opposite end of said conductor and normally engaged with said dead-end anchoring means, said clamping means releasably engaged with said dead-end anchoring means to temporarily disconnect the electrical circuit and releasably engageable with said ground or neutral connection.

5. In an electrical circuit breaker structure including a stationary terminal, a grounded support including a dead-end anchoring means insulated therefrom and electrically connected to the line, said support supporting said terminal in insulated relationship thereto, and a ground or neutral connection; a conductor electrically connected on said support with said stationary terminal and comprising a flexible section, a circumjacent resilient means and a releasable clamping means normally electrically connected to the line, said clamping means releasably engaged with said dead-end anchoring means to temporarily disconnect the electrical circuit and releasably engageable with said ground or neutral connection.

6. In an electrical circuit breaker structure including two stationary terminals, a means for electrically connecting and disconnecting said terminals, and a grounded support including a ground or neutral connection; a dead-end anchoring means electrically connected with the line and positioned in the proximity of each terminal and insulated therefrom, a by-pass conductor adapted to temporarily provide a by-pass circuit between each of said dead-end anchoring means, and flexible conductors each including a releasable clamping means at one end and normally providing exclusively an electrical circuit between each of said stationary terminals and its corresponding dead-end anchor means, said releasable clamping means releasably engaged with said dead-end anchor means to temporarily disconnect the electrical circuit and releasably engageable with said ground or neutral connection.

7. In an electrical circuit breaker structure including two stationary terminals, a means for electrically connecting and disconnecting said terminals, and a grounded support including a ground or neutral connection; a dead-end anchoring means electrically connected with the line and positioned in the proximity of each terminal and insulated therefrom, a by-pass conductor adapted to temporarily provide a by-pass

circuit between each of said dead-end anchoring means, and conductors normally providing an electrical circuit exclusively between each of said terminals and its corresponding dead-end anchor means, said conductors comprising a flexible section, a circumjacent resilient means and a releasable clamping means releasably engaged with said dead-end anchoring means to disconnect the electrical circuit and releasably engageable with said ground or neutral connection.

8. In an electrical circuit breaker structure including a stationary terminal, a grounded support including a dead-end anchoring means insulated therefrom and supporting said terminal in insulated relationship thereto, and a ground or neutral connection on said support; a flexible conductor normally providing an electrical circuit between said stationary terminal and said dead-end anchoring means and comprising a current carrying wire, rigid sections extending from 15 said terminal and supporting said wire, said sections each pivotally linked with one another and including a releasable clamping means at the free end, said clamping means electrically connected with said wire and normally electrically 25 connected with the line, said clamping means releasably engaged with said dead-end anchoring means to temporarily disconnect from the line and releasably engageable with said ground or neutral connection.

9. A device for isolating a pole top switch or the like from an electric line, comprising a flexible disconnect loop permanently attached to a stationary terminal of said switch, releasable

5 connecting means affixed to the other end of said loop for engaging the line to said switch, an adjacent grounding connection arranged to receive said releasable connecting means, said adjacent grounding connection being part of the dead-end anchoring means of said line and insulated therefrom.

10. The method of conjointly maintaining service in an electric high tension power line and electrically isolating a circuit breaker having two switching elements movable relative to each other to open and close the line circuit and having line terminals each electrically connected respectively to one of said switching elements and through a conducting link to said line, said method comprising in sequence, temporarily electrically by-passing said breaker by means of a jumper shunting said breaker, disconnecting said breaker from said power line at said conducting links, and establishing a connection between said terminals and ground or neutral through said conducting links.
